UNITED STATES PATENT OFFICE.

JOSEPH BUTCHER, OF NEW YORK, N. Y.

PENDULUM-REGULATOR FOR CLOCKS.

SPECIFICATION forming part of Letters Patent No. 709,594, dated September 23, 1902.

Application filed February 21, 1902. Serial No. 95,008. (No model.)

To all whom it may concern:

Be it known that I, JOSEPH BUTCHER, a citizen of the United States, residing in the city, county, and State of New York, have invented 5 certain new and useful Improvements in Pendulum-Regulators for Clocks, of which the following is a specification.

This invention relates to means for regulating a clock-pendulum by varying its length; 10 and it has for its object to provide a single and accurate device which may be operated from the outside of the clock-case and one which may be adjusted to suit cases of different dimensions or heights.

15 In the accompanying drawings, which illustrate an embodiment of the invention as adapted to an electric clock, Figure 1 is a vertical section of the clock-case, taken through the center of the dial and showing the regulator mainly in side elevation. Fig. 2 is a plan of a part of the top of the case. Fig. 3 is an elevation of the pendulum and a part of the regulator, as seen from the left in Fig. 1. Fig. 4 is a plan of the pendulum-fork.

20 1 designates the base, 2 the top, and 3 the front, of the clock-case, only a part of which is shown, as the particular form, size, and ornamentation of the case are not important to my invention.

25 4 designates the clock-movement as a whole, and 5 the dial.

On the verge-arbor 6 in the movement-frame is the crutch-wire 7, having at its lower end a fork 8, (seen in plan in Fig. 4,) to receive the 30 stem or rod of the pendulum 9. By "pendulum" is here meant the bob and the rod carrying it. At the upper end of the pendulum-rod is attached the pendulum-spring 10, engaging the crotch 11. The effective length 40 of the pendulum is measured from the crotch 11 down to the bob of the pendulum, and this length is varied according to the present invention by raising or lowering the pendulum, the spring 10 playing through the crotch 11.

45 The means employed for raising or lowering the pendulum comprises a screw 12, fixed to the upper end of the spring 10, and a wheel-nut 13 on said screw and rotatively mounted in collared bearings in a bracket 14 on some part 50 of the movement-frame or on some adjunct thereto. As shown in Fig. 1, it is on a pillar of the frame, in which is formed the crotch

11. The wheel-nut 13 gears with a pinion 15, fixed on an upright arbor 16, which has a bearing below in the bracket 14 and extends upward telescopically into a tubular arbor 17. This arbor 17 projects upward through the top of the clock-case into a recess 18 in said top, where it is provided with a suitable thumb-piece 19 for rotating the arbor. Practically the arbors 16 and 17 are one, they being secured together by a set-screw 20 or some other securing device. The object in making the arbor 17 telescopic is to enable it to be conveniently varied in length to suit the device to varying conditions, and obviously any devices equivalent to the telescoping of the arbors may be employed for the purpose. A wicket-plate 21 may be employed to close the recess 18, so as to exclude therefrom dust and the like. The fork 8 is flared at its ends, as shown in Fig. 4, so as to prevent the pendulum from escaping too readily from the fork when the clock is being moved about or tilted. A lining-cup 22 in the recess 18 may have radial graduations 23, if desired, as seen in Fig. 2, for effecting nice regulation or adjustment of the pendulum in regulating the clock.

Obviously my regulator may be employed with any pendulum-clock and is not limited 80 to use with an electric clock. I have shown this regulator in my application for patent for an electric clock filed October 16, 1901, under Serial No. 78,785, and allowed January 6, 1902; but it is merely shown as an adjunct and is not claimed therein.

I do not wish to restrict myself to the specific construction of the regulating device as herein shown. Obviously mechanical equivalents may be employed in lieu of the elements 90 shown without departing in any material degree from my invention.

Having thus described my invention, I claim—

1. The combination in a clock, of the pendulum, the spring forming a prolongation of the latter, the screw on and forming a prolongation of said spring, the crotch in which said spring plays, the nut on said screw, means for collaring said nut, and means for 95 rotating said nut for raising and lowering the pendulum.

2. The combination with a clock-case and a clock inclosed therein, of the clock-pendu-

lum, the flat spring forming a prolongation of said pendulum, the crotch, a screw device for raising and lowering the pendulum, and means for operating said screw device, said 5 means comprising an arbor extending out at the top of the clock - case, a thumb - piece thereon occupying a recess in the top of the case, and a pinion thereon gearing with the wheel-nut of the said screw device.

10 3. The combination with the case of a clock, having a recess in its top, an arborex- tending down from said recess and having a pinion 15 at its lower end, and the said pinion, of the crotch, the pendulum, its spring, 15 engaging said crotch, the screw on the upper end of said spring and parallel with said pinion-arbor, and a collared wheel-nut on said screw and gearing with said pinion.

4. The combination with a clock-case hav- 20 ing a recess in its top, and an extensible ar- bор extending down into the case from said recess, of the clock-pendulum, its spring, the crotch which said spring engages, the screw

on said spring, and the collared wheel-nut on said screw.

25 5. The combination with the movement- frame of a clock provided with a crotch for the pendulum-spring, and the case of the clock, having a recess in its top, of the pen- dulum, its spring, engaging said crotch, the 30 screw on and forming a prolongation upward of said spring, the wheel-nut on said screw, the means on the movement-frame for collar- ing said nut, a telescopic and extensible ar- bор dependent into the case from the recess 35 in the top thereof and parallel with the said screw on the pendulum-spring, a thumb- piece on said arbor in said recess, and a pinion on said arbor and in gear with said wheel-nut.

In witness whereof I have hereunto signed 40 my name, this 18th day of February, 1902, in the presence of two subscribing witnesses.

JOSEPH BUTCHER.
